US00D604430S

(12) **United States Design Patent**
Mugge et al.

(10) **Patent No.:** **US D604,430 S**
(45) **Date of Patent:** **** Nov. 17, 2009**

(54) **MOLDED SURFACE OF A CONCRETE PRODUCT**

(75) Inventors: **Jimmie L. Mugge**, Eagan, MN (US);
Ronald J. Scherer, Shakopee, MN (US);
David M. La Croix, Circle Pines, MN
(US)

FIG. 1 is a lower, right perspective view of a molded surface of a concrete product according to our new design;

FIG. 2 is a front elevation view thereof;

FIG. 3 is a top view thereof;

FIG. 4 is a bottom view thereof;

FIG. 5 is right side elevational view thereof; and,

FIG. 6 is a left side elevational view thereof.

The broken lines in the drawings illustrate an embodiment of the structural environment of a concrete product that includes a molded surface of the design and is not part of the design sought to be patented.
